UNITED STATES PATENT OFFICE.

STEPHEN I. FEKETE, OF DETROIT, MICHIGAN, ASSIGNOR TO HUDSON MOTOR CAR COMPANY, OF DETROIT, MICHIGAN, A CORPORATION OF MICHIGAN.

DOOR LATCH.

Application filed April 8, 1926. Serial No. 100,612.

This invention relates to latches designed primarily for use in connection with the doors of closed automobile bodies, and especially to latches of the type comprising a latch bolt, outside operating means including a handle at the outer side of the door for retracting the bolt, separate inside operating means including a handle at the inner side of the door for retracting the bolt, and means, operable by manipulation of the inside operating means, for preventing retraction of the bolt by the outside operating means. The invention has for its general object to provide a latch of this type of simple, inexpensive, and compact construction which can be easily assembled and in which the proper operation of the several parts is insured.

The more particular objects of the invention, together with means whereby the latter may be carried into effect, will best be understood from the following description of a preferred embodiment thereof illustrated in the accompanying drawings, in which:

25 Fig. 1 is a plan view of the latch.

Fig. 2 is an elevation looking from the outer side of the door and with the cover plate removed, the spindle of the outside operating mechanism being shown in section.

30 Figs. 3 and 4 are sections taken on the lines 3—3 and 4—4, respectively, Fig. 2.

The latch casing comprises two spaced parallel plates including a base plate 10 and a cover plate 11 having hooked lugs 12 engaging slots 13 in the plate 10, whereby said plates are held in assembled relation. The base plate 10 is formed with guides 14 for a sliding latch bolt 15 having longitudinally spaced projections 5 and 6 providing bearing surfaces which cooperate with the outside and inside operating mechanisms, respectively, the operative end 17 of the latch bolt projecting through an opening in an angular end portion 18 of the base plate 10. The end 17 of the latch bolt is normally projected into operative position by a coil spring 21 one end of which engages a bearing surface 22 formed on the latch bolt and the other end of which is secured to the base plate 10 by lugs or fasteners 23 secured to or formed integral with said plate. The lock casing is designed to be secured to the inner side of the door (not shown) with the angular portion 18 extending about the free edge of the latter and the operative end 17 of the latch

bolt normally projecting from said free edge.

The outside operating means comprises a handle 24 located at the outside of the door, said handle being mounted on a spindle 25 which extends through the door and is operatively engaged with a roll-back 26 which cooperates with the bearing surface at the end of the projection 5 on the latch bolt. The roll-back 26 is formed with a hub portion 27 journaled at its ends in the plates 10 and 11 and is of a thickness substantially corresponding to the spacing of said plates so as to be engaged by the latter at opposite sides. The spindle 25 is preferably of square or other non-circular cross section and engages a correspondingly shaped opening in the hub 27 in the roll-back 26, thereby providing a driving connection between said roll-back and spindle.

The inside operating mechanism comprises a handle 28 at the inner side of the door and a spindle 29 having a non-circular portion which engages a non-circular opening in a sleeve or hub 30 journaled at its ends in the plates 10 and 11 respectively. The sleeve 30 or hub 30 is formed intermediate its ends with an enlarged non-circular portion 7 located between said plates and on which is mounted an operating member 32 having a projection 33 which constitutes a roll-back 80 cooperating with the bearing surface on the projection 6 of the latch bolt. The spindle 29 is journaled in an escutcheon plate 34 which may be secured by bolts or screws 35 to clinch nuts 36 carried by the base plate 10. 90

The mechanism for preventing retraction of the latch bolt by the outside operating means comprises a dog 37 pivoted at one end, as at 38, to the base plate and having its free end extended into proximity to the outside roll-back 26. The dog 37 is of less thickness than said roll-back and its free end is normally disposed opposite or in the path of movement of a notch 39 in the latter so as not to interfere with the retraction of the 100 latch bolt by the outside operating mechanism. The free end of the dog is engaged by a leaf spring 40 carried by a pin 41 projecting from the base plate 10, said spring tending to depress the free end of the dog 105 out of the path of movement of the notch 39 and into a position to restrain the roll-back 26 against operation. In this connection it will be seen that the dogging means operates to restrain the roll-back of the out- 110

side operating mechanism while leaving the latch bolt itself free, so that the door may be closed whether the latch mechanism be dogged or not. The dog 37 is normally held with its free end opposite the notch 39 against the tension of the spring 40 by engagement of a projection 42 formed thereon intermediate its ends with the periphery of a cam portion 43 of the operating member 32. Said periphery is formed with a notch 44 adapted, when said operating member is turned into one angular position, to receive the projection 42 and permit the spring 40 to depress the free end of the dog 37 out of the path of movement of the notch 39 and into operative position.

Since the end of the dog 37 cooperates with the notch 39 in the outside roll-back 26, said dog is of less thickness than said 20 roll-back, and the operating member 32 may also be made of a thickness corresponding substantially to that of the dog. In order therefore to hold said member against movement longitudinally of the sleeve 30, as well 25 as to retain the latter in its operative position, the portion 45 of the cover plate 11 adjacent said sleeve is preferably dished inwardly, as shown in Fig. 4, to engage the outer face of said operating member and the 30 enlarged portion 31 of said sleeve.

The arrangement of the parts above described is such that when the operating member 32 is turned in a counter-clockwise direction from the neutral position shown 35 in Fig. 2 the roll-back portion 33 thereof will operate to retract the latch bolt. When said member is turned in the opposite or clockwise direction from the position shown, the projection 42 enters the notch 44, thereby 40 permitting the spring 40 to move the free end of the dog 37 out of the path of movement of the notch 39 and into position to engage the outside roll-back 26.

In order to prevent accidental dogging of 45 the latch by impact of the projection 6 upon the roll-back 33 when the latch is retracted and suddenly released, means are provided for yieldingly arresting the operating member 32 in its neutral position when moved 50 thereinto from either direction. Said means as shown comprises a leaf spring 46 secured at one end by a lug or fastener 47 to the base plate 10, said spring having adjacent its free end a centering projection 48 55 adapted to engage a recess 49 in the roll-back 33 when said operating member is in neutral position. Said spring is also preferably formed intermediate its ends with a second centering projection 50 adapted to 60 engage the notch 49 when the member 32 is turned in a clockwise direction into dogging position, thereby insuring the entry of the projection 42 into the notch 44 and assisting the spring 40 in yieldingly holding the parts 65 in dogging position against accidental dis-

engagement. Movement of the operating member 32 in the dogging direction may, if desired, be further limited by a stop stud 51 on the base plate 10 and engaged by the roll-back 33.

Having thus described my invention, I claim:

1. In a latch for vehicle doors, a sliding latch bolt having longitudinally spaced bearing surfaces, a spring for projecting 75 said bolt, handles located respectively at the inside and outside of the door, laterally spaced spindles operated by said handles respectively, roll-backs on said spindles cooperating respectively with the bearing 80 surfaces on said bolt to retract the latter, a dog cooperating with the roll-back on the outside handle spindle to restrain the latter while leaving the bolt free, and a cam 85 on the inside handle spindle for controlling said dog, said inside handle spindle being movable by its handle from a neutral position in one direction to cause the roll-back thereon to retract said bolt and in the opposite direction to cause said dog to restrain 90 the roll-back on said outside handle spindle.

2. In a latch for vehicle doors, a latch bolt, a spindle operable from the outside of the door, a roll-back on said spindle for retracting said bolt, a dog for restraining 95 said roll-back, a second spindle operable from the inside of the door and spaced from said first named spindle, and a second roll-back on said second spindle having a cam 100 portion for operating said dog, said second spindle being movable from a neutral position in one direction to cause said second roll-back to retract said bolt and in the opposite direction to cause said dog to restrain 105 said first named roll-back.

3. In a latch for vehicle doors, a latch bolt, a spring for projecting the same, latch actuating means operable from the outside of the door, means for dogging said latch actuating means, latch actuating means 110 operable from the inside of the door, said last named means being movable from a neutral position in one direction to retract said bolt and in the opposite direction to cause said dogging means to dog said first named latch actuating means, and means for yieldingly arresting said last named actuating means in neutral position when moved thereinto from either direction.

4. In a latch for vehicle doors, a latch bolt, a spring for projecting the same, latch actuating means operable from the outside of the door, means for dogging said latch actuating means, latch actuating means 115 operable from the inside of the door, said last named means being movable from a neutral position in one direction to retract said bolt and in the opposite direction to cause said dogging means to dog said first named latch actuating means, and means 120 for yieldingly arresting said last named actuating means in neutral position when moved thereinto from either direction.

- for yieldingly retaining said last named actuating means in either neutral or locking position.
5. In a combined latch and lock for vehicle doors, a latch bolt, a spring for projecting the same, latch actuating means operable from the outside of the door, means for dogging said latch actuating means, latch actuating means operable from the inside of the door, said last named means being movable from a neutral position in one direction to retract said bolt and in the opposite direction to cause said dogging means to dog said first named latch actuating means, and comprising a combined bolt-engaging roll-back and dog-controlling cam member, and a centering spring cooperating with said member to hold the same in either neutral or dogging position.
- 20 6. In a latch, the combination with a latch bolt, and retracting means for the bolt including members spaced longitudinally of the bolt, of a spring pressed pivoted element for dogging one of said members normally held inoperative by the other member.
7. In a latch, the combination with a latch bolt, and retracting means for the bolt including roll-backs spaced longitudinally of the bolt, of means for dogging one of said roll-backs normally held inoperative by the other roll-back, and yieldable means for automatically moving the means aforesaid into operative dogging position when released by the second roll-back.
- 35 8. In a latch, the combination with a latch bolt, and a member for retracting said bolt, of a pivoted element for dogging said member, a second bolt retracting member having means for rendering said dogging element inoperative, and yieldable means for automatically moving said pivoted element into operative dogging position when the second bolt retracting member is in a predetermined position.
- 45 9. In a latch, the combination with a latch bolt, and a roll-back for retracting said bolt, of means for dogging said roll-back, a second bolt retracting member having means for rendering said dogging means inoperative, and yieldable means for automatically moving said dogging means into operative dogging position when the second bolt retracting member is in a predetermined position.
- 55 10. In a latch, the combination with a latch bolt, and a member for retracting said bolt, of an element for dogging said member having a projection, a second bolt retracting member having means for rendering said dogging element inoperative and having a recess therein for receiving said projection, and yieldable means for automatically moving said element into operative position when said recess receives said projection.
- 60 11. In a latch, the combination with a latch bolt, and a member for retracting said bolt, of a pivoted element for dogging said member having a projection intermediate of its ends, a second bolt retracting member having spaced rounded surfaces alternatively engageable with said projection for rendering said dogging element inoperative.
- 70 12. In a latch, the combination with a latch bolt, and a roll-back for retracting said bolt, of an element for dogging said roll-back having a projection, a second bolt retracting member having means for rendering said dogging element inoperative and having a recess therein for receiving said projection, means for automatically moving said element into operative position when said recess receives said projection, and means for yieldably holding the second bolt retracting member when the recess receives said projection.
- 75 13. In a latch, the combination with a latch bolt, and a member for retracting said bolt, of means for dogging said member including an element movable into the path of said member, a second bolt retracting member having means normally holding said element in inoperative position and having other means for permitting said element to move into inoperative position when said second mentioned member is in a predetermined position, and means for moving said element into operative position when said second mentioned member is in said predetermined position.
- 80 14. In a latch, the combination with a latch bolt, and a member for retracting said bolt, of means for dogging said member including a pivoted arm movable into the path of said member, a second bolt retracting member having means normally holding said arm in inoperative position and having other means for permitting said arm to move into operative position when said second mentioned member is in a predetermined position, and yieldable means for alternately moving said arm into operative position when said second mentioned member is in said predetermined position.
- 85 15. In a latch, the combination with a latch bolt and a member for retracting said bolt, of a pivoted arm for dogging said member, yieldable means urging said arm to operative dogging position, and a second bolt retracting member normally holding said arm in inoperative position against the tension of said yieldable means.
- 90 16. In a latch, the combination with a latch bolt, and a member for retracting said bolt, of means for dogging said member, a member having an arm for retracting said bolt and having other means for actuating said dogging means, and yieldable means engageable with said arm for detachably holding the second mentioned member in various positions of adjustment.

17. In a latch, the combination with a latch bolt, and a member for retracting said bolt, of a pivoted element for dogging said member having a projection intermediate of its ends, a second bolt retracting member having a rounded surface engageable with said projection for rendering said dogging element inoperative and having a recess adjacent to said rounded surface for receiving said projection so as to permit said element to dog the first mentioned bolt retracting member.

In testimony whereof I affix my signature.

STEPHEN I. FEKETE.
